AUTOMATICALLY OPERATIVE VALVE

Filed June 18, 1928

FIG. I.

FIG. II.

INVENTOR:

ROBERT J. DOUGHERTY,

By *Arthur E. Paige*
Attorney

UNITED STATES PATENT OFFICE

1,927,259

AUTOMATICALLY OPERATIVE VALVE

Robert J. Dougherty, Ambler, Pa., assignor to
 John Wood Manufacturing Company, Con-
 shohocken, Pa., a corporation of Pennsylvania

Application June 18, 1928. Serial No. 286,087

1 Claim. (Cl. 137—153)

The improvement in flow-controlled gas wa-
 ter heaters disclosed in this case is claimed in
 my copending application Serial No. 364,600 filed
 May 20, 1929.

5 My invention is particularly applicable to gas-
 fired water heaters such as described in appli-
 cation Serial No. 171,237 filed February 26, 1927
 by Victor Mauck for Letters Patent of the United
 States, and particularly a house heating system
 10 including such a heater with thermostatically
 controlled valves such as described in Victor
 Mauck's application Serial No. 187,590 filed April
 29, 1927 for Letters Patent of the United States.

Such heaters include cellular units comprising
 15 congeries of primarily cylindrical thin copper
 tubes, the ends of which are expanded and sold-
 ered together, so that the tubes afford passage-
 ways for products of combustion to heat water
 contained in the space around said tubes. In such
 20 heating systems, it is necessary to forcibly cir-
 culate the water to prevent accidental overheating
 of the soldered portions of such units and
 consequent disintegration thereof, and it is pref-
 erable to effect such circulation by an electrically
 25 operated pump. However, such pumps are of
 course, liable to be rendered temporarily inopera-
 tive by abnormal condition of their supply cir-
 cuit, for instance, by the blowing of a fuse. Unless
 30 means are provided to practically instantaneous-
 ly shut off the supply of gas to the burner of
 such a water heater upon cessation of operation
 of the means for circulating the water, serious
 35 damage to the heater may result, for, at its maxi-
 mum consumption of gas, such a burner is cap-
 able of melting the solder from the joints in
 the portion of such a heater unit adjacent the
 40 burner in approximately ten seconds after ces-
 sation of operation of the pump.

I have not been able to find upon the market
 45 any thermostatically controlled means for shut-
 ting off the gas supply to such a burner within
 the time thus limited. Therefore, the general
 purpose and effect of this invention is to provide
 means which are practically instantaneously op-
 erative to shut off or shut down to a minimum,
 the supply of gas to a burner as the consequence
 of cessation of operation of a pump embodied
 in such a heating system as above contemplated.
 50 However, it is obvious that my invention is of
 more general application and, therefore, I do
 not desire to limit myself to the specific embodi-
 ment thereof herein described.

As hereinafter described, my improved valve
 55 includes a disk in cooperative relation with an
 annular seat and held between two metallic bel-

lows which are subjected to internal pressure
 from respectively opposite sides of the pump;
 said valve being held off its seat to permit the
 flow of gas thru the latter when the pump is
 not operating but being closed upon its seat to 60
 shut off the supply of gas, when the pump is
 operating.

My invention includes the various novel fea-
 tures of construction and arrangement herein-
 after more definitely specified. 65

In said drawing; Fig. I is a longitudinal sec-
 tional view of an automatically operative valve
 embodying my invention.

Fig. II is a diagram showing the essential ele-
 ments of a gas-fired water heating system em-
 bodying elements with which said valve is adapt-
 ed to cooperate to control the supply of gas to
 the heater burner. 70

Referring to Fig. I; the cylindrical tubular cas-
 ing 1 has gas ports 2 and 3 extending thru its side
 wall at respectively opposite ends thereof, and the
 annular valve seat 5 intermediate of said ports,
 in cooperative relation with the valve disk 6 which
 is normally held off its seat by the corrugated
 cylindrical tubular bellows 7 and 8, which extend
 upon respectively opposite sides thereof in coaxial
 relation therewith. Consequently, said casing 1
 normally establishes communication between said
 gas ports 2 and 3 thru said seat 5. The outer ends
 of said bellows 7 and 8 are respectively rigidly
 connected with plugs 9 and 10 which have screw
 threads 11 and 12 respectively engaging the op-
 posite ends of said casing 1. The inner ends of
 80 said bellows 7 and 8 are respectively rigidly con-
 nected with disk heads 14 and 15. Said head 15
 has the screw threaded socket 17 for axially ad-
 justable and detachable engagement with the
 stem 18 of said valve disk 6 so that the latter is
 85 rigidly connected with said bellows head 15. Said
 valve 6 has the axially opposite stem 19 fitted
 in the seat 20 in the bellows head 14; so that said
 valve disk 6 is resiliently supported in coaxial
 90 relation with its annular seat 5 but is axially ad-
 justed so that it is normally held off said seat, as
 shown.

As hereinafter described, said bellows 7 is sub-
 jected to internal pressure by water from the in-
 take conduit 22 of the pump 23, shown in Fig. II,
 whereas, said bellows 8 is subjected to internal 105
 pressure by water from the discharge conduit 24
 of said pump; so that when said pump is operat-
 ing, the internal pressure in the bellows 8 exceeds
 that in the bellows 7 and the valve disk 6 is closed
 110 upon its seat to thus shut off communication be-

tween the gas ports 2 and 3 at opposite ends of said casing.

Referring to Fig. II; 26 indicates the main gas burner of the heater above contemplated, which is supplied with gas thru the conduit 27, and the function of said valve 6 in the embodiment shown in Fig. II is to stop the supply of gas thru said conduit 27 when said pump 23 is for any reason stopped.

10 The conduit 28 leads from a municipal gas main or other source of fuel gas under pressure and is connected with the casing 29 below the seat 30 for the main diaphragm valve 31, which is carried by the flexible diaphragm 32 so that it normally gravitates to closed position, to prevent the flow of gas thru said conduit 27 to said burner 26.

However, said gas conduit 28 is continually in communication with the gas conduits 33 and 34, which are connected with said diaphragm valve casing 29 merely for convenience of assembly. Said conduit 33 leads directly to the pilot burner 35 which is normally lit. Said conduit 34 leads directly to the port 2 in the automatic valve casing 1 aforesaid; so that the space at the right-hand side of the valve disk 6 in Fig. I is continually directly connected with the gas supply conduit 28. The port 3 of said valve casing 1 is connected with said main diaphragm valve casing 29, above the diaphragm 31 in the latter, by the conduits 36 and 37; so that, when said valve 6 is open, which is its normal, idle, condition; said diaphragm valve 31 is subjected, upon both sides, to the normal pressure of the gas supplied thru the conduit 28, and is then held closed not only by gravity, but by reason of the greater area of said diaphragm 32 exposed to said gas pressure above than below said seat 30.

Said gas conduit 37 is in communication with the switch diaphragm casing 39 below the flexible diaphragm 40 therein, so as to normally uplift said diaphragm when the valve 6 is open. Said diaphragm 40 is operatively connected with the electric switch lever 41 which is in cooperative relation with the switch terminals 42 and 43 so that, when said diaphragm 40 lowers, said terminals 42 and 43 are permitted to come in contact and close the circuit between the conductors 45 and 46 to then energize the electric motor 47 which operates the pump 23.

60 In order to automatically initiate the operation of said main burner 26 and water pump 23; I provide the gas bleed pipe 48 thru which the gas from the conduit 37 may escape into the conduit 34 leading to the pilot burner 35, under control 65 of three thermostatically operative valves, to wit, first, the valve 50 which has the thermostatic tube 51 extending in the hot water fitting 52 of the heater system; which valve is set to close at, say, 200° F. Second, the valve 54 having the thermostatic element 55, is adapted to close at some room temperature, say 70° F., and, third, the safety valve 57 having the thermostatic element 58 and adapted to close when the temperature local to the burner 26 falls below a predetermined degree. However, said thermostatic element 58 is adapted to maintain said valve 57 open whenever the pilot burner 35 is lighted so as to maintain the flame 59.

In order to insure sufficient gas pressure in said 70 conduit 37 to uplift the switch diaphragm 40 when the valve 6 is closed; I provide said main diaphragm valve 31 with a bleed port 60 thru which sufficient gas is supplied to the conduit 37 to uphold said switch diaphragm 40 under normal 75 idle conditions. I also prefer to include in said

conduit 37 a fitting 61 constricting the effective area of said conduit to such a degree as to permit the flow therethru of the volume of gas admitted thru the bleed port 60, but offering sufficient resistance to the large volume of gas from the conduit 36 to insure instantaneous closure of the diaphragm valve 31 whenever said differential valve 6 is opened.

The normal cycle of operation is as follows: If the temperature of the room in which said valve 54 is mounted falls below the temperature for which that valve is set; said valve 54 opens and, providing that the pilot burner 35 is lighted so that the valve 57 is held open, and that the temperature of the water in the system and in the container 52 is not above the critical temperature so that said valve 50 is open; the gas pressure below the switch diaphragm 40 is relieved by the escape of gas thru the bleed pipe 48 and said diaphragm falls and effects the closure of the circuit 45, 46 of the electric motor 47 and thus starts operation of the pump 23 to begin the circulation of water in the system. As soon as such circulation is established, the difference in pressure of the water in the bellows 7 and 8 closes said valve 6, and gas flow through said valve to the space in the casing 29 above the diaphragm valve 31 being thus stopped; said valve 31 is lifted by the normal gas pressure below it and gas is thus admitted to the main burner 26 thru the valve seat 30 in the main diaphragm valve casing 29. The gas thus supplied to the burner 26 is, of course, ignited by the flame 59 of the pilot burner 35, and the heater 63 continues to operate until either of the automatic control valves 50 or 54 is closed, respectively by rise of temperature of the water in the container 52 above the critical temperature, or rise of temperature of the atmosphere in the room local to the valve 54. Closure of either of said valves 50 or 54 stops the escape of gas from the bleed pipe 48, and the gas admitted thru the bleed port 60 uplifts said switch diaphragm 40, breaking the circuit of the motor 47 and stopping the operation of the pump. The instant the pump stops, said valve 6 (which has been held closed by the pressure of water incident to the operation of the pump,) opens, thus admitting the full gas pressure above the main diaphragm valve 31 closing the latter and thus instantaneously stopping the supply of gas to the main burner 26 and thus preventing any danger of overheating and disintegrating the water containers 63 above the same.

However, although my improved automatically operative differential valve was designed for inclusion in the complex system indicated in Fig. II; it is susceptible of use in other embodiments. Moreover, it may be so adjusted that it is normally shut and may be opened by difference of pressure in the bellows 7 and 8 instead of being closed by difference in pressure in said bellows.

Therefore, I do not desire to limit myself to the precise details of construction, arrangement, or method of operation herein set forth, as it is obvious that various modifications may be made therein without departing from the essential features of my invention, as defined in the appended claim.

I claim:

In an automatically operating valve structure; the combination with a tubular casing having ports extending thru the circumference thereof

transversely to the axis of the casing and in spaced relation; an annular valve seat rigidly connected with said casing, between said ports; screw plug closures respectively fitted to the opposite ends of said casing; corrugated metallic bellows respectively rigidly connected at their outer ends to said screw plugs and having closure heads at their inner ends, and adapted to exclude the fluid in said casing from said bellows; 5 a valve carried by and between said bellows heads and continually in contact therewith and fitted to close on said seat and prevent communication between said ports; said bellows adapted to continually press said valve in respectively opposite directions; said plugs having fluid ports opening thru them into the respective bellows; whereby said valve is held stationary when the fluid pressure in said bellows is substantially equal, and said valve is shifted with respect to its seat when the fluid pressure in one of said bellows exceeds that in the other; including an axial pivotal connection between said valve and one of said bellows heads; and a screw thread on said valve; whereby said valve may be freely rotated in continual contact with said head and is adapted for axial adjustment, independently of any fluid pressure.
